BUILDING CONSTRUCTION

Robert W. McLaughlin, Jr., New York, N. Y., assignor to American Houses, Inc., New York, N. Y., a corporation of Delaware

Application September 25, 1936, Serial No. 102,451

8 Claims. (CL 20—4)

This invention relates to building construction, and more specifically to prefabricated buildings.

In general, it is an object of the invention to provide a device of the character described which will efficiently perform the purposes for which it is intended, which is simple and economical of construction, which can be expeditiously, conveniently and safely manipulated, and which can be readily manufactured and assembled.

Other objects of the invention are to provide a building unit which may be interchangeably used throughout the flooring or the wall or the ceilings or the roof; to provide such units which interlock; to provide a simple keying arrangement for interlocking such units; to provide such units which may be fabricated at the factory and interlockingly assembled at the place where the building is to be erected, preferably without the use of rivets, nails or the like; to provide such units which may have heat-insulating material added as or before they are assembled; to provide such units which may be assembled into buildings of various types of room lay-out; and to provide such units which may be used as connecting conduits at the same time as units for floor or wall structure.

Another object is to provide interchangeable, prefabricated units which, when assembled, form a self-supporting structure.

Another object is to provide a building, the walls of which are, at least in part, suspended from the floor; to provide such a building, the ceilings of which are suspended from the walls; and to provide interlocking suspending means accomplishing this.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

Figure 1 is a plan view, in section, of a construction embodying one form of the invention;

Fig. 2 is a perspective view, partly in section, of a construction like that shown in Fig. 1, with certain parts removed and certain parts added;

Fig. 3 is a perspective, more detailed view of certain of the elements shown in Fig. 2;

Fig. 4 is a sectional view, in elevation, of the elements shown in Fig. 3 and in conjunction with certain other elements normally adjacent thereto and shown in Fig. 2; and

Fig. 5 is an elevational, sectional view of a ceiling and roof which may be used in conjunction with the parts shown in Figs. 1 and 2 and which embody one form of the invention.

This invention contemplates a house or other building, the great majority of the parts of which may be manufactured into relatively large-sized units at the factory and which may be erected simply by the interlocking of these together at the site of the building, without the use of bolts, rivets, nails or the like.

A principal unit, as shown in Fig. 1, comprises a panel 10, which may be of plywood, board or other suitable material, and two stud elements 12 which are attached to the panel by any convenient means, such as nails or rivets, or by a suitable adhesive, along the long edge of the panel. This trough-like element may be used in the roofing where the panel becomes the support for the roof proper. It may be used in the ceiling. When it is used in the partitions, a second panel element 11 may be carried by the stud elements parallel to, and spaced from, the panel 10. The unit may be used as an outer wall, in which case any suitable covering elements such as brick veneer, metal lathe and stucco, shingles, or ship lap siding 14 with lap siding 16 thereon may be positioned parallel to panel 10 to serve as the outside of the building. The unit may be used in constructing a floor. In this last instance, a panel 111, which may be of any suitable insulating material, may serve as a protection against the dampness of the ground and may also serve to form the unit into a conduit whereby hot or cold air, piping, or wires may be carried about the building.

The various units employed in the building are preferably of the same breadth, and all floor units are preferably of the same length, as are all wall units and all ceiling units. It is to be understood that if the units employed are of a width of two feet or less it may be desirable in certain parts of the building, as for example where doors or windows are to be positioned, to employ a plurality of units formed into a single structural unit with portions cut away to permit the insertion of the door or window element, which in turn may be provided with suitable standard frame elements and the like. It is intended,

however, that basically the structural units embodying the present invention, if intended as wall units, may be interchangeably employed anywhere in the wall structure of the building. The 5 same is true of the units intended as floor or ceiling or partition or roofing units.

It will be understood also that although certain elements may be termed studs or joists throughout this specification, these elements are 10 in fact preferably similarly formed stud or beam-like elements of sheet metal. In the claims it is to be understood that the use of the word "stud" or the words "stud elements" is to be deemed to include elements of this type where employed 15 specifically as studs or as joists or the like.

The unit is shown in cross-section in Fig. 1 in an upright wall. The studs 12, which may be of sheet metal, such as steel, each have a surface attached to a surface of the panel by 20 such means as a rivet screw, or nail 13 (see Fig. 2), or by any suitable adhesive. Each stud is shaped or bent to provide a concavity 18, closely adjacent the panel. The stud elements are positioned at the ends of the panel elements, and 25 where the structural units are assembled in adjacent position, with the stud elements of adjacent units abutting, these concavities of adjacent stud elements face in the same direction and nest or interlock, one within another, the 30 one extending out over the edge of the panel and the other in from the edge of the panel, as shown in Fig. 1. Each stud element has a second concavity 20 closely adjacent its other end, spaced from and parallel to but facing oppositely from 35 the first-mentioned concavity in that stud. Immediately beyond the concavity 20, i. e., distal from the panel 10, each stud element is bent parallel to the panel 10 in a flat portion 22. Each stud element may have a flat portion 24 between 40 the two concavities.

It will be seen that the stud on the right of the central unit at the top of Fig. 1 fits into the stud element on the left hand edge of the next unit to the right. A locking or keying member 26, preferably also of thin sheet metal, is used to hold the two adjacent studs together. This member may be very simple, comprising a flat surface 28 with ends 30 bent around the flat ends 22 of the contacting stud. If desired, the key 45 26 may be attached to a piece of wood 32 as by a nail or other element 34 before the element is affixed in place. The element 32 may extend the length of the key 26, and may be of any material to which may be screwed or nailed, or otherwise attached, the second panel or wall closure element.

It is to be understood that the key 26 need not extend the full length of the stud element. Sections of the key element of short length may be affixed at the factory to the cooperating element 32, so that a section of such element with a short key at each end thereof may be provided, or short sections of the key element and its cooperating element 32 may be successively positioned one above the other to cover the face of the two internesting adjacent stud elements. If desired the secondary panel or wall-covering elements may be prefabricated of such width as to coincide with the width of the structural unit. 50 The wall-covering elements may, for example, be formed as a slab of material of such width as accurately to coincide with each wall panel element.

At the factory, the panel 10 is attached to its 75 two studs 12. A plurality of such units are sent

to the site of the building, aligned vertically, in the case of a wall, side by side, with the studs fitting into each other. A locking element 26, with attached strip of wood 32, is slipped down so as to lock each unit with the next unit by holding together the two distal parts of the two adjacent studs. In the case of an outer wall, the outer wall surface may then be attached to the wooden strips 32 so as to form a series of hollow, upright compartments. These may be left empty, or may be filled with insulating material such as mineral wool, 35.

The foregoing describes the assembly of any series of units generally. The following is a description of the construction of a building having various types of structural units, one forming the floor, one the walls, another the roof, etc.

Fig. 2 shows portions of two walls which meet at right angles and which extend upward from the floor, which is supported by a peripheral 20 foundation, all as seen from the outside of the building in projection. The actual corner, where the walls meet, has been cut out to show certain details of the floor and the keying of the latter to the walls. A foundation 36 is provided 25 on which the ends of a series of interlocking units are laid. These units each have a main panel, here numbered 110, which forms the floor of the building or room and, if desired, a lower panel, here 111, which is a protection against dampness 30 and the like. Joists 112 spacedly position the panels in each unit. Attached along the long side of each outer unit is a keying element 138, hereinafter more specifically described.

A series of outer-wall units, which have been 35 fabricated at the factory, is now set up with the panels 10 facing inward. The stud elements 12 which form a part of each of the wall units are longer than the panels 10 by an amount such that when the lower ends of the studs 12 are 40 positioned adjacent the foundation 36, the panels 10 have their lower edges in registry with or extending only slightly below the floor panels 110. Keying elements 38 are suitably attached as by rivets 40 to the upright studs 12. The 45 elements 38 are interkeyed with the keying element 138 on the floor unit, the latter supporting the former. In this way, the entire wall may be supported from the floor. It may also, if desired, be supported in part by the foundation 36. Or it may be entirely supported by the 50 foundation and merely keyed to the floor units.

It should here be noted that the keying elements 38, which are riveted or otherwise affixed to the lower ends of the vertical stud elements 55 of each wall structural unit, and the keying elements 44, which are similarly affixed to the upper ends of the same stud elements of the structural wall units, act as braces to provide with the studs a rigid frame for each wall element. 60 They thus perform a double function, acting not only as keying elements but also as supporting and bracing elements. The same is true of the keying elements 142 associated with the floor units, which act in cooperation with the joists 65 112 to provide a rigid, braced steel structure for those units. The ceiling units are similarly designed and will be apparent hereafter.

Across the end of each floor unit is provided a keying element 142 which is attached by wings 70 143 to the webbing of the floor joists 112. The keying elements may have been affixed to the studs by welding or rivets at the place of manufacture of the units. Another series of vertical units, aligned in a horizontal row, with a key- 75

ing element 42 similar to the keying element 38, is set up along the ends of the floor units and is keyed to, and thereby suspended from, the keying elements 142 of those units.

5 A corner unit, to connect the two vertical walls, is provided. This is not shown in Fig. 2, but may be seen, in plan, in Fig. 1. Corner units are constructed by using a corner panel 210 of the desired angle. The stud elements, which extend away from the ends of the panel 210 are, in this case, not parallel to each other, but at an angle. Each, however, is parallel with, and fits into, a stud element on the adjacent unit, one adjacent unit being in one wall and the other adjacent unit being in the other wall. The corner element may also have keying elements which fit into; and may be supported by, the keying elements 138 and 142 of the floor unit which extends into the corner.

20 Any suitable outer wall covering elements may be affixed to the upright wooden strips 32, to which are nailed the locking elements 26. Mineral wool 35 may be inserted into the hollow, upright compartments formed by the upright units and covering elements. It should be noted that the insulating material may, if desired, be put in place at the factory.

25 A ceiling is provided as follows (see Fig. 5): The upright studs 12 of the wall units extend upwardly beyond the inner wall panels 10 and have keying elements 44, similar to keying elements 42, suitably attached to them. These are in reversed position vertically as compared with keying elements 42 because the latter are used to support the wall from the floor, while keying elements 44 are used to support the ceiling from the side walls. A series of units is brought together side by side in a horizontal row so as to form a ceiling. The main panels 310 face downward. The joists 312, associated with these panels, have keying elements 344 similar to the keying elements 142 at the ends of the floor units. They are reversed in position because they are to be suspended from the keying elements 44 at the top of the wall units 12. The keys 344 have wings 343 to attach them to the ceiling unit studs 312. Along the long side of those ceiling units which are at the edge of the ceiling, there may be provided a keying element, not shown, but corresponding to the keying element 138 which extends along the long side of those floor units which are at the edge of the floor, and this ceiling keying unit, not shown, may be interlocked with, and be supported by, a keying element, not shown, which is horizontal and fixed to the tops of the studs and those wall units which are successively adjacent the long side of the edge unit of the ceiling.

30 Each end of each ceiling unit may be supported, as shown for one end only at 344 and 44 in Fig. 5. However, there may be a partition in the building with surface panels 10 and 11 separating the interior of the building into rooms. In such a case, one end of each ceiling unit is suspended, as shown at 344 and 44, and the other one of each ceiling unit may rest on one of the panels 10 or 11 of the vertical partition unit or on the studding associated therewith. A second series of ceiling units having ceiling panels 311 may be similarly supported from an outer wall, not shown, and rest on partition panel 11.

35 Keying elements 45 and 345 may key together the ends of the ceiling units which rest on partition panels 10 and 11 respectively. There may not be a second panel parallel to, and above,

panel 310 and carried by the ceiling unit joists 312. When the upper panels are lacking, the ceiling from above looks like a plurality of tightly packed troughs. Material 35 may be inserted in these troughs to prevent the transfer of heat. 5

10 The keying elements have a central portion 70 extending lengthwise thereof (see Fig. 3). Along one edge there is a U-shaped extension 72, each arm of which is parallel with, but not in the plane of, the central portion 70. Along the other lengthwise edge of the element, there is a flat portion 74 parallel with, but not in the plane of, the central portion 70. It will be seen that two such elements may be interkeyed, the portion 74 of one fitting into the U-shaped extension 72 of the other. Whichever one is to support the other has its U-shaped extension facing upwardly along its lower edge. Thus, the extension of keys 142, 138, 44 and 345 is along the lower edge, while the extension of keys 38, 42, 344 20 and 45 is along the upper edge.

25 Attention should be drawn to the shape of the keying elements. It should be noted that the U-shaped extension portion of each element and the flat portion adapted to internest or interlock 25 with a U-shaped extension portion of a cooperating keying element are displaced forwardly from the plane of the central portion of the keying element. This displacement is of such nature and of such extent as to permit the interlocking or interkeying units to be moved into interlocked position vertically and without lateral displacement of either unit. If, for example, it is desired to remove a single wall panel unit before the roof is fixed in position, the unit 30 may be lifted vertically and without lateral displacement until the keying elements are completely disengaged. Elements such as are shown in the drawings and which are designed with both the U-shaped extension and the flat extension laterally displaced from the central portion may be adapted to permit such adjustment without difficulty. 35

40 Roofing also may be supplied and formed from prefabricated units similar to the other units in the building, the main panels 410 being on the upper side. One series of units may extend slopingly upward from the top of one wall, and another set from the top of an opposite wall, and be upheld centrally by a keystone element 76. 45 To this latter, a ridge pole and associated roofing devices, not shown, may be attached. The outer, lower ends of the studs 412 of the roof units are provided with a special form of key 444, which sits in, and is held by, a key 350 attached to the ceiling units. The latter key has a 50 U-shaped extension 351 into which an extension of key 444 extends. A bend in key 350 abuts a bend in key 444. The bend and the U-shaped part of key 350 support the outward thrust of 55 the roof transmitted by key 444. 60

65 It will be seen that, the weight of the roof being transmitted diagonally downward and outward against keys 350, there is set up an outward, horizontal component of that force to which the ceiling units are subjected and which 65 is transmitted to the wall elements. The keying elements 45 and 345 are therefore subjected to a stress. This, in turn, relieves the interior partition elements of at least some of the weight of 70 the ceiling elements. 75

Joists which form the side walls of various units, such as the floor units, may be provided with openings 78, the openings in one joist being in registry with the openings of a joist in the next unit, so that the units may intercommuni- 75

cate and act as conduits for the transmission of hot or cold air, pipes, etc.

It is of course to be understood that while the wall-forming units have been shown as suspended by the floor units, and while certain other units have been shown as suspended from or supporting still other units, these arrangements may be altered in any desired manner by altering the relative positions of engaging keying elements.

It should also be pointed out that the concavities in the stud elements, positioned as they are in close proximity to the cooperating panel elements, act to substantially increase the strength of said stud elements, which in general act as beams wherein an accumulation of material at the ends, such as is provided by the said concavities, is highly desirable.

Doors, windows, wall-finishing elements and roofing elements have not been shown or described, in the interest of clarity. It is to be understood that for all such purposes standard elements may be employed.

It should be noted that the structures described provide a building utilizing only dry materials in such form and condition that they may be assembled, substantially without the use of fastening elements, such as bolts, screws, rivets, nails and the like, by substantially unskilled labor.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A building construction unit comprising a panel element, a plurality of sheet metal stud elements affixed to the same face of said panel and adjacent opposite edges thereof, each of said stud elements being provided with means forming a surface spaced from said face of said panel and substantially parallel thereto, the portion of each stud element between said surface-forming means and said panel being formed with a plurality of concavities, one adjacent said panel, another adjacent said surface-forming means, and metallic elements affixed to each of said plurality of stud elements and adapted to form therewith a substantially rigid metallic frame for said unit.

2. A building construction unit comprising a panel element, a plurality of sheet metal stud elements affixed to the same face of said panel and adjacent opposite edges thereof, each of said stud elements being provided with means forming a surface spaced from said face of said panel and substantially parallel thereto, the portion of each stud element between said surface-forming means and said panel being formed with a plurality of concavities, one adjacent said panel, another adjacent said surface-forming means, and metallic elements positioned substantially parallel to said panel and affixed to each of said plurality of stud elements and adapted to form therewith a substantially rigid metallic frame for said unit.

3. A building construction unit comprising a

panel element, a plurality of sheet metal stud elements affixed to the same face of said panel and adjacent opposite edges thereof, each of said stud elements being provided with means forming a surface spaced from said face of said panel and substantially parallel thereto, the portion of each stud element between said surface-forming means and said panel being formed with a plurality of concavities, one adjacent said panel, another adjacent said surface-forming means, and metallic elements affixed to each of said plurality of stud elements and adapted to form therewith a substantially rigid metallic frame for said unit, said metallic elements being provided with keyways and being adapted to interlock with similar elements.

4. A building construction unit comprising a substantially rigid metallic frame, a plurality of substantially parallel elements of said frame comprising metallic stud-like elements irregularly shaped to internest with similarly shaped elements of similar units, a plurality of other elements of said frame comprising metallic keying members adapted to interlock with similar members of similar units, and a panel element affixed to said stud-like elements.

5. In combination, a plurality of building construction units each comprising at least a pair of similarly shaped, substantially parallel, metallic stud-like elements having a panel element affixed thereto and separated and substantially rigidly positioned by a plurality of metallic keying elements, adjacent stud-like elements of adjacent units being positioned to abut and having irregular surfaces adapted to internest with each other, and means to interlock said adjacent, abutting, stud-like elements of adjacent units.

6. In combination, a plurality of building construction units each comprising at least a pair of similarly shaped, substantially parallel metallic stud-like elements having a panel element affixed thereto and separated and substantially rigidly positioned by a plurality of metallic keying elements, adjacent stud-like elements of adjacent units being positioned to abut and having irregular surfaces adapted to internest with each other, and means to interlock said adjacent, abutting, stud-like elements of adjacent units, said interlocking means having affixed thereto means adapted to engage a wall-closing means.

7. In combination, a plurality of building construction units each comprising at least a pair of similarly shaped, substantially parallel, metallic stud-like elements having a panel element affixed thereto and separated and substantially rigidly positioned by a plurality of metallic keying elements, adjacent stud-like elements of adjacent units being positioned to abut and having irregular surfaces adapted to internest with each other, adjacent keying elements of adjacent units being adapted to engage and interlock with each other, and means to interlock said adjacent, abutting, stud-like elements of adjacent units.

8. In a building, in combination, a plurality of construction units of substantially equal width and adapted to form a floor, a plurality of wall units of substantially the same width as said floor units, and means comprising similarly-shaped elements affixed to said floor and said wall units for interlocking said wall units with said floor units, said wall units being supported by portions of said floor units other than the upper surface thereof.

ROBERT W. McLAUGHLIN, JR.
